UNITED STATES PATENT OFFICE

2,282,201

LIFT TRUCK

Jacob J. Neuman, South Salem, N. Y., assignor to
 United States Patent Development and Royalty
 Company, South Salem, N. Y.

Application October 18, 1940, Serial No. 361,776

11 Claims. (Cl. 214—113)

The present invention relates to lift trucks, such as shown in Patent No. 2,178,368, and more particularly to the load carrying members thereof.

In the lift trucks usually employed in the pallet system of handling articles, a great deal of difficulty has been experienced due to the breakage of the edge boards of the pallets by the load carrying members. This is especially so when pallet loads are being taken down from high tiers due to the inability of the operator from his position to gauge the correct height of the members in order to properly enter the pallet. He thus very often has the members too high or too low and they strike and break the edge boards.

Another source of breakage to the pallets has been due to failure of the operator, when pulling the members out, to lower them sufficiently or to lower them too much.

It has been attempted in the past to remedy these difficulties by protecting the pallet edge boards with steel angles, sheet metal, etc. This made the pallets too expensive and not wholly satisfactory. A further attempt to solve the problem was by making the members blunt to prevent splitting of the pallet boards and while this latter attempt improved matters, the hard metal ends of the members still do considerable damage to the pallets.

It is an important object of the present invention to provide load carrying members which will not be subject to the disadvantages above mentioned.

Another object of the invention is to provide the members with feeler and buffer means.

A still further object of the invention is to provide load carrying members which indicate to the operator of the truck when the members have been correctly or incorrectly applied.

A still further object is to provide buffer means which are simple and inexpensive and which are easily applied and renewed.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a side elevational view with parts broken away showing a lift truck with the invention applied to the lifting member and co-acting with a pallet.

Figure 2 is a fragmentary end view of the parts shown in Figure 1.

Figure 3 is a top plan view with parts broken away of the lifting member with the invention applied thereto.

Figure 4 is a side elevational view with parts broken away of the parts shown in Figure 3.

Figure 5 is a sectional view taken along the line 5—5 of Figure 3.

Figure 6 is a sectional view taken on the line 6—6 of Figure 3.

Figure 7 is a sectional view taken on the line 7—7 of Figure 3.

Figure 8 is a top plan view with parts broken away of a lifting member with a modified form of the invention applied thereto.

Figure 9 is a fragmentary top plan view of a lifting member with another modified form of the buffer means applied thereto.

Figure 10 is a similar fragmentary top plan view with a still further modified form of the buffer means applied thereto.

Figure 11 is a side elevational view of the lifting means with the buffer means shown in Figure 9 applied thereto and showing an improved support for the lifting members.

Figure 12 is a cross-sectional view along the line 12—12 of Figure 11.

Figure 13 is a fragmentary top plan view of the lifting member with a still further modified form of buffer means.

Figure 14 is a longitudinal cross-sectional view taken along the line 14—14 of Figure 13, and

Figure 15 is a cross-sectional view taken along the line 15—15 of Figure 14.

Referring more particularly to the drawings and to the forms of the invention shown by Figures 1 to 8 inclusive, the numeral 10 designates the tip portion of a lifting fork 11 forming part 40 of the lift truck diagrammatically shown in Figure 1. The lower face of the fork 11 is given a taper 12 terminating in a beveled edge portion 13 while the upper face of the fork 11, while not tapered, is provided with a beveled edge portion 14 similar to that of 13, both of which are gradually reduced to zero.

Between these beveled portions the edge of the fork is provided with a substantially V shape channel 15 of varying depth as particularly shown by Figures 5, 6 and 7. Beginning at a point designated by lines 5—5 in Figure 3, the channel is at its greatest depth forming a pocket 16 and the channel gradually decreases in depth as designated by the line 6—6 corresponding to Figure 6 until the minimum depth is at the outer-

most edge of the tip portion 10 as designated by line 1-7 and Figure 7. In referring to this channel of varying depth and to the various designations it is understood that the same variance is true on the other side of the tip portion of member 11 although the section lines have not been applied thereto. The corners of the channel are suitably rounded to eliminate cutting edges.

A section of standard V rope or other resilient material 17 of constant width but complementary in shape to channel 15 is arranged within the channel to form buffer and feeling means for the fork 11. The ends 18 of material 17 are received in the deepest part or pockets 16 of the channel and secured to the fork 11 by clamping plates 19, shake proof washers 20 and screws 21, the latter of which are threaded into fork 11.

The pockets 16 being the deepest portions of channel 15 completely house the ends of the rope and their connecting elements to eliminate any protruding parts. In this manner the forks 11 are not liable to be entangled in anything during their use or movement of the truck.

Accordingly the rope 17 from its attaching points in pockets 16 is given a gradually increasing area of projection from the tip of fork 11. The greatest amount of rope projecting will be at the foremost portion of the tip due to the channel at this point being of the smallest depth. As this foremost portion is the one that initially comes into contact with the pallets, the greatest amount of protection is needed at this point.

It will be noted that the outer face of the V-shaped rope is sufficient to guard the beveled portions 13 and 14 of the fork 11 and this is necessary to give the tip of the fork a substantially all resilient contacting surface.

The construction shown in Figure 8 is substantially the same as that described heretofore, the only difference being in the attachment of the rope ends 18. In this modification the rope ends 18 are secured to the tip portion 10 by the same shake proof washers 20 and screws 21 of Figure 3, the clamping plates 22 in this instance being bent whereby the screws 21 are secured to the tip 10 at an angle. This manner of attachment serves to draw the rope 17 tightly into channel 15 as is obvious.

The construction thus far described permits a certain amount of "feeling" to be done by fork 11 in attempting to enter a pallet. Should the first effort to enter the pallet be unsuccessful and the fork strike the edge boards or any other part of the pallet, the resilient rope 17 will prevent any damage to the pallet or its parts.

Referring to the modification shown by Figure 9, a molded buffer 23 having a radially projecting feeler member 24 is provided for the fork 11. The manner of attachment of this modification is similar to the manner of attachment described with reference to the buffer of Figures 1 to 8.

In the modification shown by Figure 10 the resilient buffer is comprised of two sections of rope 25, each rope section having a radially extending portion 26. The extending portions 26 are joined together by rivets 27 to form a feeler member 28 similar to the feeler member 24 of Figure 9.

The operation of the construction shown by Figures 9 and 10 is of course similar to that described in the preceding figures. The feeler members 24 and 28 of these latter constructions enables the operator to adjust the forks to the correct level before attempting to insert the main forks. If the flexible feelers 24 and 28 strike the pallet boards no damage is done.

The construction shown in Figures 11 and 12 relate more particularly to the mounting of the forks 11 on the elevating carriage 29. This arrangement is designed to prevent the damage to the pallets due to failure of the operator, when pulling the forks out, to lower them sufficiently, or to lower them too much. The vertical portion 30 of the fork 11 is provided with a slot 31 through which a shaft or rod 32 extends. The rod 32 is journaled at both ends in the elevating carriage 29 forming part of the truck diagrammatically shown in Figure 1 of the drawings.

Each fork 11 is attached to the top of the elevating carriage 29 with springs 33 of sufficient strength to support the weight of the forks 11 alone but not sufficient to support the forks when they are carrying a loaded pallet. The connection of the upper ends of the springs 33 is made with an eye bolt 34 and nut 35. The nut 35 is so adjusted that when the forks 11 are unloaded they are supported at a height where the rod 32 is at the midpoint of the slot 31. It is thus seen that if the forks 11 are either slightly too high or too low when withdrawing them from the pallet that the spring 33 provides a yielding connection and no damage will result.

Referring now to the modification disclosed in Figures 13, 14 and 15 the tip of the fork 11 is provided with oppositely beveled recessed portions 36 on its upper and lower face. These recessed portions 36 follow the contour of the fork and frictionally receive therein a slideable substantially U-shaped plate 37. The outer configuration of the plate 37 is arcuate to correspond with the arcuate tip portion of the fork. A substantially V-shaped groove is provided on the periphery of the plate 37 to accommodate a similar spaced buffer, such as that shown at 23 in Figure 9 and which is provided with a feeler 24. The buffer is secured to the plate by means of bolts 38, washers 39 and nuts 40 extending therethrough, the heads of the bolts being preferably countersunk in the buffer 23 whereby the resilient contact surface of the buffer is not impaired. In order to accommodate the nuts 40 the fork tip is provided with sockets 41 into which the nuts 40 will be received when the plate 37 has been forced to its limit within the recesses 36.

The plate 37 is normally urged outwardly by means of springs 42 and 43 disposed within a bore 44 formed in the tip of the fork 11. This bore 44 extends from the edge portion of the tip and terminates in a housing 45 at a point beyond the recessed portion 36. The diameter of the bore 44 is larger at the tip portion than at its succeeding portions whereby shoulders are provided in the bore. The spring 43 is encircled about a rod 46 between two washers 47 and 48, the rod having a head portion 49. The rod is threadedly secured to the central portion of the plate 37 and the washer 47 bears against a shoulder portion of the bore 44 whereby the plate and buffer are yieldingly supported. The spring 42 is disposed within the smaller diameter of the bore 44 in contact with the head 49 of rod 46 and the head 50 of a plunger 51. The plunger 51 is part of a push button switch 52 located in the housing 45, the housing being closed by a detachable cover portion 53. Suitable wires 54 leading to a control part of the truck are disposed adjacent the housing 45 to be electrically operated by the push button 52.

In operation, when the buffer 23 strikes a pallet 75 let the plate 37 and the rod 46 slide back, the

spring 43 is compressed pushing back the plunger 51 to operate the switch 52. This switch being in the forward circuit of the driving motor of the lift truck and when operated stops this motor and applies the brakes. The operator must then back the truck away and adjust the forks to the correct elevation. When the truck is backed away the spring 43 returns the plate 37 to normal position and the forward circuit of the lift truck driving motor is restored.

The length of the various springs and the plate 37 are so proportioned that the truck will stop before the plate is pushed back to the limit of its travel. The spring 43 is of a strength just sufficient to overcome the sliding friction of the plate 37 and return it to normal position while the spring 42 is even weaker being only of a strength to operate the push button switch 52. It is thus seen that when the buffer strikes a pallet these springs give and no damage is done.

While it has been stated in all forms of the invention that the buffer means is preferably a rope it is understood that any other type of material having inherent resiliency such as rubber may be substituted therefor.

The plunger 51 is rendered detachable from the head 50 or the switch 52 in any suitable manner, such as screw threads or the like. This will permit the plunger 51 to be first inserted in the bore 44 to be followed by the spring 42, rod 46 and spring 43. After these parts have been assembled the switch 52 may be secured to the plunger 51 whereby the complete assembly is provided.

It is obvious that various changes and modifications may be made in the details of construction and design of the above specifically described embodiment of this invention without departing from the spirit thereof, such changes and modifications being restricted only by the scope of the following claims.

What is claimed is:

1. In a lift truck, in combination, a frame, a lifting member carried by an end of said frame and adapted for insertion between the faces of a two faced pallet, said lifting member having a peripheral channel and pockets at the ends of said channel, a buffer element disposed in said channel to project beyond said lifting member, and securing means for the ends of said buffer element, said securing means and ends of said buffer element being wholly disposed within said pockets.

2. In a lift truck, in combination, a frame, a lifting member carried by said frame and adapted for insertion between the faces of a two faced pallet, said lifting member having a peripheral channel of variable depth, said channel having its greatest depth at its ends to provide pockets and its smallest depth at the tip portion of said lifting member, a buffer element disposed in said channel, said buffer element having its greatest projecting portion at the tip of said lifting member, the ends of said buffer element being housed within the pockets of said channel, and securing means for the ends of said buffer element secured to said lifting member within said pockets.

3. In a lift truck, in combination, a frame, load carrying members extending from said frame and adapted for insertion between the faces of a two faced pallet, a channel on the peripheral portions of said lifting members, opposed deep pockets defining the ends of said channel, said channel progressively decreasing

and increasing in depth between said pockets, a buffer element disposed in said channel, said buffer element having projecting areas corresponding to the channel depths, and securing means for the ends of said buffer element, said securing means and ends being disposed within said deep pockets and secured to said load carrying members.

4. In a lift truck, in combination, a frame, load carrying members extending from said frame and adapted for insertion between the faces of a two faced pallet, a channel on the peripheral portions of said lifting members, opposed deep pockets defining the ends of said channel, said channel progressively decreasing and increasing in depth between said pockets, a buffer element disposed in said channel, said buffer element having projecting areas corresponding to the channel depths, and securing means for the ends of said buffer element, said securing means and ends being disposed within said deep pockets and secured to said load carrying members at an angle whereby said buffer element is drawn into said channel.

5. In a lift truck having a frame and an elevating carriage on said frame, lifting members carried by said carriage and yieldable connecting means between said carriage and lifting members, said connection comprising a spring secured to said carriage and to a vertical portion of said lifting members, said lifting members provided with an elongated slot, a transverse rod in the slots and journaled to said elevating carriage, said yieldable connection normally biasing said members to raised position, and buffer means on said lifting members.

6. In a lift truck, in combination, a frame, adjustable load carrying members extending from said frame and adapted for insertion between the faces of a two faced pallet, a channel on the peripheral portions of said lifting members, a buffer element secured in said channel and projecting beyond said lifting members to form a resilient contacting surface for the latter, and a flexible feeler member projecting from said buffer element.

7. In a lift truck, in combination, a frame, load carrying members extending from said frame and adapted for insertion between the faces of a two faced pallet, a channel of progressively increasing and decreasing depth on the peripheral portions of said lifting members, pockets formed by the greatest depth of said channel, buffer elements in said channel to progressively project from the lifting members in accordance with the depth of the channel, one end portion of each of said buffer elements being secured in said pockets, the other end portions of each of said buffer elements being connected together to form a feeler member projecting beyond said buffer elements, and securing means recessed in said pockets for the first mentioned end portions of said buffer elements.

8. In a lift truck, in combination, a frame, load carrying members on said frame and adapted for insertion between the faces of a two faced pallet, a channel on the peripheral portions of said lifting members and a moulded buffer element secured in said channel to project therefrom.

9. In a power-driven lift truck, in combination, a frame, adjustable load carrying members extending from said frame and adapted for insertion between the faces of a two faced pallet, a retractable buffer element yieldingly connected

to said load carrying members forming a resilient contacting surface for said members and normally in projected position, said buffer element adapted to be inserted between the faces of the pallet, and being retractable upon striking the pallet when said load carrying members are improperly adjusted, and means carried by said lifting members for stopping the forward motion of said lift truck, said means adapted to be actuated by said buffer element when in retracted position.

10. The combination with a power-driven lift truck having a frame, adjustable load carrying members extending laterally from said frame and adapted for insertion between the faces of a two-faced pallet, and control means on said members for stopping the forward motion of said lift truck; of a retractable buffer element slidably mounted on the free ends of said members for actuating said control means, said buffer ele- 20

ment adapted to be inserted between the faces of the pallet, and means for yieldably maintaining said buffer element in extended position, whereby upon failure of said load carrying members to be properly adjusted for entry between the faces of the pallet, said buffer element will be retracted by striking the pallet to actuate said control means.

11. The combination with a lift truck having vertically adjustable load carrying members extending laterally therefrom and adapted for insertion between the faces of a two-faced pallet; of buffer means on the free ends of said load carrying members projecting therefrom and forming resilient contacting surfaces for said load carrying members to prevent damage to the pallet upon failure of said load carrying members to be properly adjusted, and feeler means projecting forwardly from said buffer means.

JACOB J. NEUMAN.
